UNITED STATES PATENT OFFICE.

SIMON TSCHOUMAKOFF, OF PETROGRAD, RUSSIA.

ARTIFICIAL LEATHER.

1,228,848.

specification of Letters Patent. Patented June 5, 1917.

Application filed July 19, 1916. Serial No. 110,153.

To all whom it may concern:

Be it known that I, SIMON TSCHOUMAKOFF, a subject of the Emperor of Russia, and residing at Maximilianovsky Pereoulok 3, Petrograd, in the Empire of Russia, have invented certain new and useful Improvements in Artificial Leather, of which the following is a specification.

My invention relates to a new product of manufacture designed to replace the ordinary leather of animal origin. This product represents a leather of vegetable nature and is distinguished by its main constitutive part being the outer layer of the birch-bark. Any appropriate number of such outer layers of birch-bark are stuck together, the layers being disposed in such a manner that the direction of the lenticels (*i. e.* the small elongated spots penetrating such layers) cross themselves at right angles in alternate layers, and such alternate layers being separated from each other by interposing one sheet of cotton stuff (canvas) or the like.

The characteristic features of such leather of vegetable nature (which I propose to designate by the name "Betuladerma") consist in that such leather, owing to its being composed mainly of sheets of the outer layer of birch-bark, which generally contains about 50% of oily-resinous matters, has the property of not being moistened by water and being impermeable to the latter, this prop-

erty, in addition to the elasticity and relatively considerable tensile strength and resistance against punctures, permits the use 35 of such an artificial leather in lieu of the ordinary leather of animal origin (the sole leather, of course, excluded) or of rubbered fabrics.

In the accompanying figure of drawing 40 illustrating the invention *a* designates a bottom layer or sheet of the outer layer of birch bark, the lenticels *a'* of which, shown in dotted lines, run transversely of the sheet. A superimposed layer of textile fabric *b* or 45 similar material is glued onto the sheet *a*; and onto the fabric *b* is glued another layer or sheet *c* of the outer layer of birch bark. The lenticels *c'* of the sheet *c* run longitudinally of the latter and at right angles to the 50 lenticels *a'* of the sheet *a*.

What I claim is:

A leather substitute consisting of superposed pieces of the outer layer of birch bark stuck onto a textile fabric interposed 55 between said pieces, the lenticels of one piece being arranged at right angles to the lenticels of the other piece.

In witness whereof I have hereunto set my hand in presence of two witnesses.

SIMON TSCHOUMAKOFF.

Witnesses:

H. A. LOVAGUINE,
AUG. MICHIS.
